Primary Examiner — Paula Greene(74) *Attorney, Agent, or Firm* — Perkins Coie LLP(57) **CLAIM**

The ornamental design for a headphone device, as shown and described.

DESCRIPTION

FIG. 1 is a perspective view of an embodiment of a headphone device showing my new design, as viewed from the top and front.

FIG. 2 is a front profile view of the headphone device shown in FIG. 1.

FIG. 3 is a back profile view of the headphone device shown in FIG. 1.

FIG. 4 is a first side profile view of the headphone device shown in FIG. 1.

FIG. 5 is a second side profile view of the headphone device shown in FIG. 1.

FIG. 6 is a plan view of the headphone device shown in FIG. 1; and,

FIG. 7 is an inverse plan view of the headphone device shown in FIG. 1.

The details shown in broken lines illustrate features that form no part of the claimed design.
